PEDAL EXTENSION

Aloys Benedict and Margaret W. Benedict,
Los Angeles, Calif.

Application June 11, 1948, Serial No. 32,388

4 Claims. (Cl. 84—230)

1

This invention relates to an attachment for a piano and particularly pertains to pedal extension.

The structure of a standard piano is such that the pedals are at a fixed height from the floor irrespective of the requirements of the person playing the piano. When short persons or juveniles play the piano they find it difficult to adjust themselves properly to the keyboard and to the pedals. It is, of course, necessary for the player to have a convenient reach to the keyboard and this makes it difficult for the player to have any satisfactory control over the pedals. Various devices have been constructed for building up the height of the pedals so that they can be manipulated by a person having a short leg reach. Most of these devices are of a fixed or semi-permanent nature which makes it necessary for the attachments to be removed when their use is not required. There is a demand therefore for a pedal extension structure which does not require any attaching means and which may be easily placed in operative relation to the piano pedals or removed therefrom without manipulating any fastening device. It is also desirable to provide a piano pedal extension which will accommodate the foot of the player conveniently and comfortably. It is also desirable to provide pedal extension which may be disposed operatively relative to a plurality of pedals and which may be adjusted so that a selected extension may provide a solid support for one foot of the player without depressing the pedal normally associated therewith.

It is the principal object of the present invention to provide a pedal extension unit adapted to be placed in operative position and removed therefrom instantly and which will afford natural control of the piano pedals by persons of short leg reach, and which structure embodies means to convert a pedal extension to form a solid foot support without affecting the piano pedal normally associated therewith.

The present invention contemplates the provision of a structure adapted to be disposed upon the floor and which structure carries independent pedal extension members, said members providing a treadle portion and a pedal pad which will fit the pedal in a manner to hold the entire structure in a playing position when required.

The invention is illustrated by way of example in the accompanying drawings in which:

Figure 1 is a view in side elevation showing the application of the pedal extension structure to a piano.

2

Fig. 2 is a view in perspective showing the details of construction of the pedal extension and indicating it as removed from its operative position relative to a piano.

5 Fig. 3 is an end view of one form of the invention which includes means to adapt a pedal extension to form a solid support and to be ineffective in moving the pedal associated therewith.

Fig. 4 is a fragmentary view in side elevation 10 showing the details of the structure disclosed in Fig. 3.

Referring more particularly to the drawings, 15 indicates the case of a piano. Extending horizontally therefrom near its lower edge is a set of

15 pedals 11. These pedals when depressed will perform the usual functions required for piano playing. The present invention is concerned with a pedal extension structure generally indicated at 12. This comprises a base 13, which is

20 here shown in the form of a flat relatively thin plate, and in practice it has been found that it is desirable to make this plate of Bakelite or some suitable plastic material. The width of the plate as shown in Fig. 2 of the drawing is greater than 25 the width of the space occupied by the piano pedals. At the forward edge of the plate, and midway the width thereof, is a tongue 14 of reduced width. This projects beneath the piano and tends to aid in holding the structure rigidly.

30 At the outer edge of the plate 13 is a plurality of upwardly extending lugs 15 having horizontal openings through them to receive pivot pins 16. The pivot pins 16 pass through arms 17. One of

35 these arms is disposed at each end of each of the lugs 15 and extends upwardly to be attached to a treadle member 18. The arms are formed with upper flat faces 19, against which the treadle member rests and to which the treadle member is secured by screws 20. The treadle members

40 are of a width to accommodate the foot of a person playing the piano, and since the arms 17 extend to a height considerably above the plane of the top surface of the pedals 11 it will be recognized that the treadle portions are in reach of

45 the person playing the piano even though the person is short in height. The treadle members 18 extend forwardly toward the piano and are here shown as terminating in a downwardly curved portion 21. The downwardly curved portion of each treadle member rests against one of

50 a pair of seat blocks 22. Each of the blocks 22 has a recess 23 formed in its lower face, the recess being of a width greater than the width of a piano pedal. The blocks 22 are secured to the portions 21 by screws or other fastening means

indicated at 23. It is preferable that the blocks 22 be made of rubber so that there will be slight flexibility of the blocks. The recess 23 in each of the blocks is defined by side walls 24 and 25 which limit the lateral movement of the blocks with relation to the pedals and an end wall 26 which will limit the movement of the structure toward the piano and will insure that the piano will not be marred. In order to insure ease of action of the pedal extension as it bears against the upper face of the pedal it may be desirable to provide transverse ribs 27 which rest against the upper face of the pedal and which will insure that a minimum amount of friction will occur between a pedal 11 and its extension block 22 as the pedal is moved up and down.

In operation of the present invention the device is constructed as shown in Figs. 1 and 2 of the drawings and when it is ready for use the extension members 19 may be swung upwardly as indicated in Fig. 2. The member 13 may then be disposed on the floor or floor covering and moved so that its forward edge and its extension portion 14 extend beneath the piano and the pedals 11. The pedal extensions 18 are then swung downwardly so that the seat blocks 22 may register with the pedals and fit thereover as shown in Fig. 1. The person playing the piano may then occupy a suitable seat or stool which is placed so that the extension portions 18 may be easily reached by the feet of the player and disposed entirely thereon in a natural and comfortable position. The pedals 11 may then be depressed as required by pressure against the extension portions 18 by the person playing the piano. When the structure is not required it may be instantly removed without detaching any fastening means and due to its light weight may be easily carried away.

Referring particularly to Figs. 3 and 4 of the drawings another form of pedal extension is shown. It will be seen that it has the extension portions 18 and the downwardly curved portions 21. In addition to these portions, side webs 23 extend downwardly to a distance considerably lower than that of the piano pedals 11. The blocks 22 are hinged to the lower edge of the central curved portion 21 as indicated at 29. This makes it possible for the blocks 22 to swing upwardly and beneath the curved portion 21 so that they will be out of contact with a piano pedal 11. This position is indicated by dotted lines in Fig. 4. Here it will be seen that a spring clamp 30 or other suitable means may engage the free edge of the block 22 to hold it in its uppermost position. When in this position the lower faces 31 of the side webs 23 will rest on the floor and thus will provide a firm solid support for the pedal extension so that that particular pedal extension will be ineffective in imparting movement to the pedal 11. Such a support is often desirable with the "right hand" pedal. This provides comfort and ease of posture to the piano player since the right foot will be supported firmly and the left foot may manipulate the other extension.

It will thus be seen that the pedal extension structure here disclosed is simple in design, light in weight, and may be instantly disposed in a playing position or removed therefrom without the requirement of any attaching means.

While we have shown the preferred form of our invention as now known to us, it will be understood that various changes may be made in combination, construction, and arrangement of

parts by those skilled in the art without departing from the spirit of the invention as claimed.

Having thus described our invention, what we claim and desire to secure by Letters Patent is:

1. A piano pedal extension comprising a base plate adapted to rest upon the floor with its forward edge extending beneath the pedals of a piano, the width of said base plate being greater than the overall width of the pedals to be controlled; journal lugs extending upwardly from the base plate at the rearward edge thereof and spaced a distance apart to agree substantially with the spacing of the piano pedals from each other; treadle members, one for each of said lugs; a pair of parallel arms secured at their upper ends to each of said treadle members and receiving the corresponding journal lug therebetween; horizontal pins extending through said arms and lugs to pivot said treadle members on said lugs, each of said treadle members being of a width and length to accommodate the foot of a person playing the piano and having a downwardly extending portion at the free end thereof; and pedal seat blocks, one of which is carried on the free downwardly extending end of each of said treadle members, said blocks being parallel with the upper main portions of said treadle members, each block being formed with a recess into which a pedal may extend with said block resting on the upper face of said pedal, the length of the arms and the downwardly extending free end portion of each treadle member being such as to support said member with its upper main portion in a substantially horizontal plane when the pedal block of said member rests upon a pedal.

2. A piano pedal extension comprising a base plate adapted to rest upon the floor with its forward edge extending beneath the pedals of a piano, the width of said base plate being greater than the overall width of the pedals to be controlled; journal lugs extending upwardly from the base plate at the rearward edge thereof and spaced a distance apart to agree substantially with the spacing of the piano pedals from each other; treadle members, one for each of said lugs; a pair of parallel arms secured at their upper ends to each of said treadle members and receiving the corresponding journal lug therebetween; horizontal pins extending through said arms and lugs to pivot said treadle members on said lugs, each of said treadle members being of a width and length to accommodate the foot of a person playing the piano and having a downwardly extending portion at the free end thereof; and pedal seat blocks, one of which is carried on the free downwardly extending end of each of said treadle members, said blocks being parallel with the upper main portions of said treadle members, each block being formed of resilient material with a recess into which a pedal may extend with said block resting on the upper face of said pedal, the length of the arms and the downwardly extending free end portion of each treadle member being such as to support said member with its upper main portion in a substantially horizontal plane when the pedal block of said member rests upon a pedal.

3. A piano pedal extension comprising a base adapted to rest upon the floor, a pedal extension member articulately connected to the base at its outer end having a free-swinging end designed to rest upon a pedal, said pedal extension being formed with a treadle portion at an elevation above the floor, a supporting member at the free

end of said pedal extension and adapted to rest upon the floor when the pedal extension is to be used as a solid foot support, and a movable member carried on the free end of the pedal extension and adapted to move to and away from a position to rest upon a piano pedal whereby the free end of the pedal extension may swing to operate the piano pedal and the support thereby will be maintained out of contact with the floor.

4. A piano pedal extension comprising a base adapted to rest upon the floor, a pedal extension member articulately connected to the base at its outer end having a free-swinging end designed to rest upon a pedal, said pedal extension being formed with a treadle portion at an elevation above the floor, a supporting member at the free end of said pedal extension and adapted to rest upon the floor when the pedal extension is to be used as a solid foot support, and a movable member carried on the free end of the pedal extension and adapted to move to and away from a position to rest upon a piano pedal whereby the

free end of the pedal extension may swing to operate the piano pedal and the support thereby will be maintained out of contact with the floor, and a second pedal extension articulately connected to said base plate and being disposed parallel thereto, said second pedal extension resting upon a piano pedal at its free end.
